(57) **CLAIM**

The ornamental design for an electrical connector as shown and described.

DESCRIPTION

FIG. 1 is a front perspective view of an electrical connector according to the present invention.

FIG. 2 is a rear perspective view of the electrical connector of FIG. 1.

FIG. 3 is a front view of the electrical connector of FIG. 1. FIG. 4 is a rear view of the electrical connector of FIG. 1. FIG. 5 is a left side view of the electrical connector of FIG. 1.

FIG. 6 is a right side view of the electrical connector of FIG. 1.

FIG. 7 is a top view of the electrical connector of FIG. 1. FIG. 8 is a bottom view of the electrical connector of FIG. 1.

FIG. 9 is a front perspective view of an electrical connector according to the present invention.

FIG. 10 is a rear perspective view of the electrical connector of FIG. 9.

FIG. 11 is a front view of the electrical connector of FIG. 9. FIG. 12 is a rear view of the electrical connector of FIG. 9. FIG. 13 is a left side view of the electrical connector of FIG. 9.

FIG. 14 is a right side view of the electrical connector of FIG. 9.

FIG. 15 is a top view of the electrical connector of FIG. 9; and, FIG. 16 is a bottom view of the electrical connector of FIG. 9.

The dashed lines illustrate environment that does not form a part of the present invention, and no claim is made to the material illustrated with dashed lines.

1 Claim, 16 Drawing Sheets
